MOUNTING OF FAN UNITS IN VENTILATING SHAFTS

Thomas Wylie, Twickenham, England

Application October 21, 1946, Serial No. 704,698
In Great Britain April 23, 1946

6 Claims. (Cl. 230—42)

1

This invention relates to ventilating systems and, more particularly, but not exclusively, to the mounting of ventilating fan units in ventilating shafts on marine vessels.

It is an object of the invention to provide an improved ventilating system whereby a ventilating fan unit mounted in a ventilating shaft may be rendered more readily accessible for repairs or otherwise than has hitherto been the case. It is a further object of the invention to provide an improved ventilating system wherein the position of the ventilating fan may be readily reversed to reverse the direction of air flow produced by the fan.

According to the invention there is provided a ventilating system comprising a ventilating shaft containing a ventilating fan unit, wherein the fan unit is carried by a portion of said shaft which is pivotally mounted between the adjacent portions thereof about a central transverse axis so that said intermediate portion may be turned out of line with said adjacent portions to render the fan unit accessible, and turned through 180° to reverse the direction of air flow produced by the fan if desired.

The invention is illustrated by way of example in the accompanying drawings, in which—

Figure 1 is a part sectional side elevation of a ventilating system comprising a ventilating fan unit and a ventilating shaft according to the invention;

Figure 2 is a sectional plan view taken on the line 2—2 of Figure 1;

Figure 3 is a sectional side elevation taken at right angles to Figure 1, showing the intermediate portion of the ventilating shaft in two different positions, and...

Figure 4 is a perspective view of a ship's ventilator incorporating a ventilating system according to the invention.

In the particular construction shown in the drawings, a vertical ventilating shaft generally indicated at 10 which may be of circular cross section, is formed in three portions, an upper portion 11, an intermediate or middle portion 12 and a lower portion 13. The middle portion 12 is pivotally mounted between the upper and lower portions 11 and 13 respectively so that the said middle portion may be turned out of its normal vertical position, in which it is in line with the upper and lower portions, into a position in which it is at right angles to said upper and lower portions.

The middle portion 12 of the ventilating shaft 10 is mounted so that it can be pivoted as indi-

2

cated above, by means including two rectangular side plates 14 and 15 which are of somewhat greater height than the length of the middle portion of the shaft and are spaced apart in parallel relationship at a distance somewhat greater than the outside diameter of said middle portion of the shaft. The upper and lower ends of the side plates are connected by centrally apertured top and bottom plates 16 and 17 respectively, the upper and lower portions of the shaft projecting respectively through the apertures in said plates 16 and 17 and being secured therein in spaced relationship, for example, by welding or by means of angle members (not shown) or both.

The middle portion 12 of the ventilating shaft which is slightly shorter in length than the distance between the upper and lower portions 11 and 13 respectively of the shaft is pivotally between the side plates 14 and 15. For this purpose each side plate 14 (15) is provided with a hollow flanged fulcrum pin or stub shaft generally indicated at 21 which projects inwardly through a central aperture in the plate towards the middle portion of the ventilating shaft, the flange 22 on each pin 21 being bolted or otherwise secured to the plate 14 (15). The middle portion 12 of the ventilating shaft is provided substantially half way between its ends with a pair of external diametrically opposite annular trunnions 23 which are provided with annular bearings 24 carried by the inwardly projecting ends of the above mentioned fulcrum pins 21. The side plates may be reinforced by diagonal ribs 25 meeting in a central bush 26 which normally surrounds the corresponding fulcrum pin 21.

The gaps between the upper and lower ends of the middle portion 12 of the ventilating shaft and the adjacent ends of the upper and lower portions 11 and 13 respectively of said shaft are normally each closed by a sealing band generally indicated at 27 comprising two semi-cylindrical parts 28 and 29 with outwardly projecting end lugs 30 and 31 adapted to receive a fastening bolt 32. For this purpose the fastening bolt 32 may be pivoted to one end lug 31 of each pair of adjacent lugs, the other lug 30 of each pair being slotted for cooperation with said bolt 32 when the latter is in a substantially tangential position with respect to the sealing band 27, the bolt being secured in this position by means of a nut 33. The bands 27 may be located in position by pads 18 on the shaft 10 as shown.

The ventilating fan unit may comprise a ventilating fan 34 and an electric motor 35 for rotating the fan, the motor casing having sup-

porting arms 19 by which it is secured to say three equidistantly spaced supporting lugs 36 arranged around the interior of the middle portion of the ventilating shaft, the fan being disposed beneath the motor. The electric leads (not shown) to the motor 35 from a terminal plug 37 bolted to the plate 14 may pass through one of the hollow fulcrum pins 21 of the trunnion bearings 23 previously referred to, the middle portion of the ventilating shaft being provided with an appropriate aperture on the axis of the trunnion.

From the foregoing description it will be seen that in order to render the fan unit accessible, it is only necessary to remove the sealing bands 27 and rotate the middle portion 12 of the ventilating shaft 10, with the fan unit therein, out of line with the adjacent portions 11 and 13 of said shaft. Thus it will be seen that where, for example the upper portion 11 of the ventilating shaft carries a heavy cowl 38 above a ship's deck 39 as shown in Figure 4, the above procedure is considerably simpler than removing said cowl or entering the ventilating shaft to reach the fan as has hitherto been the practice.

It is to be understood that the invention is not limited to the particular construction described above. For example the ventilating shaft may be other than circular in cross section and other than vertical in position.

As previously indicated the middle portion 12 of the ventilating shaft 10 may be turned through 180° about its pivotal axis if desired to reverse the position of the fan and consequently reverse the direction of the air flow produced by the fan.

What I claim is:

1. A ventilating system including a ventilating shaft comprising an intermediate portion and adjacent portions two side plates connected by apertured top and bottom plates within which the adjacent portions of the shaft are secured, a stud shaft projecting inwardly from each side plate towards the intermediate portion of the ventilating shaft, and diagonal ribs on each side plate meeting in a central bush surrounding the corresponding stud shaft.

2. A ventilating system including a ventilating shaft having an intermediate portion pivoted between adjacent portions of said shaft, a fan unit in the intermediate portion two side plates connected by apertured top and bottom plates within which the adjacent portions of the shaft are secured and a stud shaft projecting inwardly from each side plate towards the intermediate portion of the ventilating shaft, for pivotally mounting the intermediate portion, one of said studs being hollow for the passage therethrough of elec-

tric leads to the fan motor within said intermediate portion.

3. A ventilating system comprising a ventilating shaft containing a ventilating fan unit, wherein the fan unit is carried by a portion of said shaft which is pivotally mounted between the adjacent portions thereof about a central transverse axis so that said intermediate portion may be turned out of line with said adjacent portions to render the fan accessible, and turned through 180° to reverse the direction of air flow produced by the fan if desired.

4. A ventilating system as claimed in claim 3 comprising lugs on the interior of the intermediate portion for supporting the casing of an electric motor for driving the fan.

5. A ventilating system including a ventilating shaft comprising an intermediate portion and aligned adjacent end portions, means for mounting the intermediate portion between the end portions including two side plates connected by top and bottom plates, each plate having a central aperture within which said adjacent end portions are secured, means at right angles to the axis of the ventilating shaft for pivotally mounting the intermediate portion between the end portions, and a ventilating fan unit supported by the intermediate portion, whereby the intermediate portion carrying the fan unit may be turned about an axis at right angles to the axis of the ventilating shaft.

6. A ventilating system as claimed in claim 5, wherein the means for pivotally mounting the intermediate portion consists of stud shafts projecting inwardly from each side plate toward the intermediate portion of the ventilating shaft, and a pair of external diametrically opposite trunnions mounted on the said inwardly projecting stud shafts.
